DESIGN FOR A LADY'S SUIT

Isidore Wasserman, New York, N. Y.

Application February 25, 1937, Serial No. 67,838

Term of patent 3½ years

To all whom it may concern:

Be it known that I, Isidore Wasserman, a citizen of the United States of America, residing in city of New York, county of New York, and State of New York, have invented a new, original, and ornamental Design for a Lady's Suit, of which the following is a specification, reference being had to the accompanying drawing, forming part thereof,

Fig. 1 is a front view of a lady's suit showing my new design.

Fig. 2 is a rear view thereof.

I claim:

The ornamental design for a lady's suit, substantially as shown.

ISIDORE WASSERMAN,
